Eli H. Janney.

United States Patent Office.

ELI H. JANNEY, OF ALEXANDRIA, VIRGINIA.

Letters Patent No. 77,046, dated April 21, 1868.

IMPROVED CAR-COUPING.

The Schedule referred to in these Letters Patent and making part of the same.

TO ALL WHOM IT MAY CONCERN:

Be it known that I, ELI H. JANNEY, of the city of Alexandria, county of Alexandria, and in the State of Virginia, have invented a new and useful Improvement in Railroad-Car Couplings; and I do hereby declare the following to be a full, clear, and exact description of the same, reference being had to the accompanying drawing, making part of this specification, in which—

Figure 1 represents a side elevation of a part of the front and rear end of two railroad-cars, partly shown in section in order to expose to view interior parts.

Figure 2 is a top view of part of the rear end of a railroad-car.

Figure 3 is a side view of part of the coupling-device.

The same letters of reference in all the figures denote identical parts.

My invention consists in constructing an automatically-working car-coupling, in such a manner that the coupling and uncoupling are performed without endangering the operator's life by going between the cars. The link intended to couple two cars together is placed and kept in an inclined position, resting its lower end against the oscillating-catch, leaning its upper end on a support attached for that purpose to the platform of the car.

When the coupling is to take place, the shock of the two cars, when running against each other, will force the link forward, and it will fall over the oscillating-catch of the other car, and both cars are coupled together.

In order to enable others skilled in the art to make and use my invention, I will proceed to describe its construction and operation.

A is a part of the front end of one car, and A' is a part of the rear end of an adjacent car. B is the draw-head, resting in a bumper, C, firmly attached to the under side of the platform or truck. A coiled spring, C', keeps the draw-head in its place, and allows it to move forward and backward under the force to which it is subjected.

D is a latch, turning on a pivot fixed to the sides of the draw-head at D'. As the part of the latch towards the inner side of the draw-head is heavier than the other part, which tapers off and nearly touches the oscillating-catch E, the latch D will occupy a horizontal position, and the lip E'', of the oscillating-catch E, will keep it in place.

E is an oscillating-catch, placed at the mouth of the draw-head in a vertical position. The upper part or neck is, at its inner side, provided with a depression, in which the link is engaged. Immediately above it is the projection or lip E'', against which the latch D rests. The pressure from above of the link will force the end of the latch down, and permit the link to drop and occupy a horizontal position, as shown in fig. 1. The latch, liberated from the downward pressure, will again assume its horizontal position, and prevent the link from disengaging itself by rising upwards. The oscillating-catch E has, at its inner side, and near its lower end, a shoulder, E''', on which the movable bar F rests. The lower edges of catch E are rounded, in order to facilitate its turning on pivot E'.

The bar F is actuated by lever I, and may be moved backward from the position shown in fig. 1, (in which it holds the catch E in a vertical position,) so as to allow the catch E to turn on pivot E', as shown in fig. 3.

The movable bar F is drawn from the shoulder of catch E when the cars are to be uncoupled. The strain of the link on the neck of the catch E will force it forward, as shown in fig. 3, and the link will be disengaged and the uncoupling is effected. I is a lever, which actuates the bar F. Fig. 1 shows the lever in the inclined position it has when not worked. In such position it will be kept by the spiral spring I', attached to the cut-side of draw-head B, and there keep the lever over the shoulder of the catch E. G is a link, of ordinary construction. H is a support or rest, to keep the link in an inclined position. It may be made of strong wire, or other suitable material, hinged to the upper face of the platform, said wire H having a shape somewhat analogous to a W, as shown in fig. 2.

When in use, it is thrown forward, as shown in black lines in fig. 2, and when not used it is thrown back.

ward on the platform, resting in a recess made for that purpose, as shown in red lines in fig. 2, in order that it may not be a hindrance to people passing over it.

If found inconvenient, or not practical, the rest H might be dispensed with, and the link, while standing on its end, might be accommodated in vertical grooves A'', cut in the platform itself, as shown in fig. 2 in red lines.

I propose to have the part of the platform over the coupling cut out and hinged to the platform, as shown in figs. 1 and 2 in red lines. The strain of the link G on the catches E does not prevent or hinder the uncoupling. The manner in which the link is disengaged from the catches E is shown in red lines in fig. 3.

I do not confine myself to the precise mode of construction herein described, as the same may be varied more or less; but

What I claim, and desire to secure by Letters Patent, is—

1. The combination of the oscillating-catch E, mounted upon a pivot, E', in the mouth of a draw-head, B, the movable bar F, lever I, and latch D, when constructed and arranged substantially as and for the purpose set forth.

2. The support or rest H, when used as and for the purpose set forth.

ELI H. JANNEY.
